UNITED STATES PATENT OFFICE.

FRANCIS H. TULLEY AND WILLIAM F. SMIESTER, OF BROOKVILLE, INDIANA.

SECTIONAL ROOF FOR SILOS.

1,011,281.

Specification of Letters Patent. Patented Dec. 12, 1911.

Application filed August 31, 1910. Serial No. 579,957.

To all whom it may concern:

Be it known that we, FRANCIS H. TULLEY and WILLIAM F. SMIESTER, citizens of the United States, residing at Brookville, in the county of Franklin and State of Indiana, have invented certain new and useful Improvements in Sectional Roofs for Silos; and we do hereby declare the following to be a full, clear, and exact description of the invention, such as will enable others skilled in the art to which it appertains to make and use the same.

This invention relates to improvements in silos, and more particularly to the roof.

The object of the invention is to provide a simple, economical and durable roof structure, which may be conveniently opened for the introduction of material from the top of the silo.

The invention also comprehends improvements in the specific details of construction and arrangement of parts which will be hereinafter described, and particularly pointed out in the claim.

In the drawings: Figure 1 is a side elevation of the upper portion of a silo with our improved roof in position. Fig. 2 is a plan view with a portion removed to better illustrate the rafter construction. Fig. 3 is a plan view of the roof supporting frame. Fig. 4 is a view similar to Fig. 1, but showing the roof sections thrown open. Fig. 5 is a detail perspective view of one of the roof sections. Fig. 6 is a similar view of the roof supporting frame.

The same numerals refer to like parts in all the figures.

1 indicates a cylindrical or other shaped silo of any approved construction. Mounted on top of the silo 1 is a frame 2 composed of end and side bars 3 and 4. Each of the said end and side bars is preferably formed of two boards of substantially the same length and securely spiked together as shown at 5.

Each board extends at one end over the adjacent board forming the bar, to provide a mortise 6. This construction avoids the necessity of accurate cutting, and also permits of the use of cheap timber. The mortised ends are fitted into each other and bolts 7 fasten them together. The end and side bars 4 and 5, are secured at their central portions to the top edge of the silo 1 by lag screws 8, and at the corners by brackets 9.

The brackets are each provided at their upper end with an outwardly bent portion 10,

formed with an opening to receive one of the screws 7. The lower end of the bracket is bent downwardly to engage the outer surface of the silo, and is formed with openings 60 for the passage of bolts 11. The frame is therefore firmly bolted to the silo, and at its corners it is supported by the angularly disposed brackets, which support the roof structure about to be described.

Firmly fastened to the side bars 4—4 are gable frames 13, each comprising a base board 14, two upwardly inclined bars 15—15, and an intermediate brace bar 16, suitably secured together and provided with a 70 corrugated sheathing 17.

The roof proper is composed of two or more hinged sections 18—18 and each section comprises a frame 19, and a sheathing 20. Each frame consists of a series of upwardly 75 inclined transverse braces 20', corresponding to the inclination of the rafters 15, and formed with a series of mortises 21, in which fit the reduced ends of a series of longitudinally disposed rafters 22. The upper edge 80 of each frame is cut at an angle to form a neat and tight joint when the frames are folded. Over this frame-work the sheathing 20 is fastened. Each section is hinged to the end bars 3, as indicated at 25, a slight distance from the lower outer edge, the overhanging portion 26 of the section serving to shed the water falling on the roof, and at the same time acts as an abutment to limit the movement when the roof sections are 85 thrown open as shown in Fig. 4.

We provide dowel pins 28, at the upper edge of one roof section and openings 29, in the edge of the adjacent section, to form a firm joint, and also form a locking connection between the sections when they are in closed position. Links or hooks 31, are pivoted on the inside of each section, and engage eyes 32 on the gables, whereby to hold the sections in open position when filling the 100 silo from the top.

A silo roof constructed as above described, will permit of the roof sections being thrown open on their hinges whereby the silo can be conveniently filled from the top, and when 105 said sections are closed they serve the purpose of an effective roof.

When the sections are thrown in open position, as shown in Fig. 4, the overhanging portions abut against the silo and prevent 110 said sections being swung outwardly too far, and therefore act to brace the parts, which

with the hooks or links firmly hold the sections in their open position.

Having thus described our invention what we claim is:—

- 5 The combination with a silo, of a horizontally disposed rectangular-shaped frame upon the upper edge thereof and having its opposite corners projecting beyond the circumference of the said silo, oppositely disposed triangular end frames secured to the upper edges of the ends of the rectangular frame, corrugated, wind-diverting end closures secured to the end frames, with their opposite edges projecting beyond the said 10 triangular frames, hinged roof sections secured to the opposite sides of the rectangular frame and adapted to rest upon the upper converging sides of the triangular end

frames, plates secured to the roof sections, with the sides overlapping the corrugated 20 end closures, brackets supporting the ends of the rectangular frames, hooks carried by the roof sections for the purpose of supporting said roof sections in open position, and dowels adapted to engage openings formed 25 in the adjacent edges of the roof sections whereby the same will be held together against displacement, substantially as and for the purposes set forth.

In testimony whereof we affix our signatures in presence of two witnesses.

FRANCIS H. TULLEY.
WM. F. SMIESTER.
